UNITED STATES PATENT OFFICE.

WILLIAM N. JACKSON AND JAMES H. HAMMOND, OF ATLANTA, GEORGIA.

DESIGN FOR A MEDAL.

SPECIFICATION forming part of Design No. 24,783, dated October 8, 1895.

Application filed September 3, 1895. Serial No. 561,357. Term of patent 3½ years.

To all whom it may concern:

Be it known that we, WILLIAM N. JACKSON and JAMES H. HAMMOND, citizens of the United States of America, and residents of Atlanta, in the county of Fulton and State of Georgia, have made a certain new and useful Design for Medals; and we do hereby declare the following to be a full, clear, and exact description of the invention, such as will enable others skilled in the art to which it appertains to make and use the same, reference being had to the accompanying drawing, and to letters of reference marked thereon, which forms a part of this specification.

15 The accompanying drawing illustrates the face of the medal.

This medal is intended to be circular in form, and its essential features are a cotton-bale A (shown in perspective in relief) and

rays B, diverging therefrom substantially in all directions, while below said bale are shown clasped hands C, and above same a phenix D, rising from her bed of flame and ashes, while above and to the back of the phenix is a scroll E of fanciful form.

Having thus described our design, what we claim as new, and desire to secure by Letters Patent of the United States, is—

The design for a medal substantially as herein set forth.

In testimony whereof we hereunto set our hands in the presence of two subscribing witnesses.

WILLIAM N. JACKSON.
JAMES H. HAMMOND.
